GAS HEATED EMBOSSED PRESS

Henry Lish, Brookline, Mass.

Application June 8, 1944, Serial No. 539,290

1 Claim. (Cl. 101—9)

1

This invention relates generally to the art of the manufacture of decorative materials and objects and more particularly to novel means and methods of producing embossing on planar materials, either of woven or knitted textile or homogeneous materials such as felt, paper or pulp board.

It has been known in the art to produce decorative objects, for example, flowers which have petal or leaf structure composed of felt or similar material in which the veinings or surface undulations are produced by heat and pressure. Such prior constructions and the methods for producing them, have been open to a number of objections, among them being the fact that the process of producing the surface irregularities was slow and time consuming with a consequent high cost of production.

It is, therefore, among the objects of the present invention to provide novel and useful decorated material and objects which may be fabricated in large scale at relatively low cost.

Another object herein lies in the provision of means for the fabrication of the said decorated materials and articles, which is convenient in use and which may be operated at relatively high speed by operators having relatively no special skill.

One of the objections to prior art constructions is that under adverse conditions in use, such as heat, pressure and humidity or combinations of these elements, the decorative veinings and undulations tend to disappear. Another object herein lies in the provision of structures and methods which provide for decorative materials or articles which show a greater durability in use in that they tend to retain their original configuration for longer periods under adverse conditions of use.

The present invention provides not only for an improved product, but a substantial uniformity in the characteristics thereof so that fabricated parts are completely interchangeable.

These objects and other incidental ends and advantages will more fully appear in the progress of this disclosure and be pointed out in the appended claim.

In the drawings, similar reference characters designate corresponding parts throughout the several views of the separate embodiments.

Figure 1 is a plan view of a five petaled flower body constructed in accordance with the invention.

Figure 2 is an enlarged vertical sectional view as seen from the plane 2—2 on Figure 1.

2

Figure 3 is an enlarged fragmentary vertical sectional view showing the male and female die elements and associated structure.

Figure 4 is a reduced fragmentary top plan view of the female die element shown in Figure 3.

Figure 5 is a side elevational view showing the male and female die elements and connected structure associated with a hydraulic press for the operation thereof.

Figure 6 is a stack of the petal blanks in one stage of the process of the fabrication of the petal forming bodies.

Figure 7 is a plan view of one of the petal blanks prior to the embossing thereof.

Figure 8 is a top view in perspective of the male die element with connected structure.

Figure 9 is a bottom perspective view of the female die element with connected structure.

Figure 10 is an enlarged fragmentary vertical sectional view as seen from the plane 10—10 on Figure 8.

Figure 11 is a reduced fragmentary front elevational view showing the association of the male and female die elements on Figures 8 and 9 with another form of press.

Turning first to the machines for the production of the embossed petal bodies, a press such as the hydraulic press 11 may be used with plane 30 plates (not shown) as a blanking press and the material 12 may be arranged in a laminated manner with a plurality of laminations superposing each other. By the use of a blanking die, the entire "lay" may be blanked with a single downward movement of the plunger or piston 13 of the press 11, with the consequent production of the stack 14 of petal bodies, the individual petal bodies being generally indicated by reference character 15.

40 The male die element 16 is preferably arranged so that it superposes the female die element 17. The principal advantage of this is that the female die element has a plurality of receptacles 18, which act to receive and properly position the individual petal body blanks, prior to, during and after the embossing operation. The female die element, therefore, may include a plurality of the receptacles 18 and as seen in Figure 4, there has been shown a female die element having nine 45 separate receptacles 18, each adapted to receive a separate petal body. The lower surface 19 of the female die element 17 is provided with a plurality of supporting and attaching lugs 20. The lugs 20 may be of block shape and are preferably 50 provided with orifices 21 which are adapted to

be engaged by the upper ends of hook connectors 22. The connectors 22 are provided with hooks at the upper ends thereof engaging the last described orifices and the lower ends thereof may be detachably secured to the plate 23, secured upon the post 24. The post 24 may be connected in any suitable manner to the platform 25 of the press 10. The female die element 17, preferably at the periphery 26 thereof and in the upper surface 27, is provided with a plurality of sockets 28, which are adapted to slidably receive the pegs or keys 29 on the male die element 16.

The receptacles 18 preferably have vertical side walls 30 which are adapted to engage the free edges 31 of the petal bodies 15. The bottom walls 32 of the receptacles 18 are provided with indentations 33 which correspond to the projections 34 on the male die element 16 as will more fully hereinafter appear.

The male die element 16 has the undersurface 35 thereof provided not only with the keys 29 but also with the male die members 36. The male die members 36 have vertical walls 37 which are adapted to slidably engage the vertical walls 30. The lowermost surfaces of the male die members 36 have the projections 34 thereon previously described.

While the configurations of the receptacles 30 and the male die members 36 are illustrated in the drawings as corresponding to the edge 31 of the petal body 15 and to the veining generally indicated by reference character 40, it will be obvious to those skilled in the art to which the present invention relates, that where desired, the die receptacles 18 and the male die members 36 may be altered to conform to any desired decorative shape or embossing.

The upper surface 41 of the male die element 16 is provided with a plurality of support members 42. The support members 42 preferably comprise bosses 43 having threaded rods 44 projecting vertically upward therefrom. The threaded rods 44 may penetrate correspondingly disposed orifices in the cross-head 45. The rods 44 are maintained in adjusted positions thereof with respect to the cross-head 45 by the use of the upper and lower nuts 46 and 47, respectively. The cross-head 45 may be adjustably positioned upon the vertical rods 48 by the use of the nuts 49 and 50. The rods 48 are vertically slidably reciprocatable within the hollow ways 51 of the press 10 by any suitable source of power. They may be, for example, elevated to the upper position thereof by springs, not shown, and lowered to the lower position thereof by pedal pressure, steam, magnetic force, or hydraulic force.

Each of the die elements 16 and 17 is provided with upper and lower heating means 52 and 53, respectively.

The heating means 52 includes a substantially circular pipe 54 which includes a plurality of horizontally disposed orifices 55 (see Figure 10). The end of the pipe 54 is provided with a cap 59 and said pipe is secured upon the upper surface 41 by brackets or clamps 56. The relatively open end of the pipe 54 curves upwardly away from the surface 41 and has attached thereto by the connector 57, a tube 58 adapted to carry gaseous fuel.

The heating means 53 includes a substantially circular pipe 64, which includes a plurality of horizontally disposed orifices 65. The end of the pipe 64 is provided with a cap 69 and said pipe is secured upon the undersurface 19 by brackets or clamps 66. The relatively open end of the 75 pipe 64 curves downwardly away from the surface 19 and has attached thereto by the connector 67, a tube 68 adapted to carry gaseous fuel.

In accordance with the invention, the method of operation is as follows: First, layers of material are plied or laminated to produce a "lay" of the desired number of layers and a suitable blanking die is forced through the "lay" to produce the stack 14 of blanks of petal bodies 15. As previously stated, the outline or edge 31 of the body 15 may be varied to suit the aesthetic requirements of the design of the finished decorative article.

For efficiency in operation, it is preferable that the "lays" be of the same number of laminations as there are receptacles 18 in the male die elements 16. Thus, the operator may handle individual stacks and deal out one of the bodies 15 into each of the receptacles 18, for each complete pressing operation cycle. The tubes 58 and 68 are connected to a suitable source of gaseous fuel (not shown) and it is desirable that sufficient pressure exist within the tubes 58 and 68 and hence the pipes 54 and 64, so that the flames of the burning gas may extend horizontally from the orifices 55 and 65 toward each other to make sufficient contact with the surfaces 41 and 19, so that the die elements 16 and 17 may reach proper operating temperature. In actual operation, it is necessary that the flames be ignited some period of time before the first batch of pressings are made so that the proper temperature is obtained. The proper operating temperature is sufficient so that the bodies 15 are properly deformed without scorching them.

By virtue of the keys 29, the die elements 16 and 17 may be properly vertically aligned with respect to each other and by virtue of the adjustment afforded by the nuts 46, 47 and 49, 50, the die elements 16 and 17 may be properly aligned with respect to each other so that they are parallel and so that each of the die members 36 may properly seat itself within the corresponding receptacle 18 with a consequent uniform pressure placed upon each of the blanks of the bodies 15, which is disposed in each of the receptacles 18. By virtue of the fact that the tubes 58 and 68 are flexible, the movement of the die members 16 and 17 with respect to each other, is relatively uninhibited.

After the individual blanks of the material 12 in the form of the bodies 15 have been placed within the receptacles 18 and the die elements are of the proper temperature, the die elements 16 and 17 are brought together under the requisite pressure and for the length of time necessary to stabilize the material 12 into its newly deformed contour.

At the end of the present operation the male die is separated from the female die and the individual petal bodies as they appear in Figures 1 and 2 are removed. Where desired, camber or other deformity may be caused to occur in the several petals 70. Although in the petal body 15 shown in Figure 1, the veining is depressed to the undersurface 71, where desired this intaglio deformation may be reversed to produce an upwardly embossed effect.

Turning now to the alternate form of the machine shown in Figure 5, for the purpose of avoiding needless repetition, parts corresponding to those just described are given the same reference characters with a prefix "1." It will be noted from this figure that the general organization and construction is the same with the exception

that the male and female die elements 116 and 117 have been altered so that they may be carried by the plunger or piston 13 of the hydraulic press 11 and the pedestal 9 respectively. In the press 11, the hydraulic tubes are indicated by the reference characters 7 and 8 while the frame and base of the press are indicated by the reference characters 6 and 5 respectively.

By virtue of the uniform distribution of the heat produced in the die elements by the present invention, each of the individual petal bodies 15 is of substantially uniform character with respect to the others in the same batch and in the construction shown, the speed of production is nine times as great in comparison with single presses in which only a single pair of individual male and female die parts are associated. Furthermore, by virtue of the relatively uniform distribution of heat and the great pressure which may be applied to the material as it is worked, the finished decorative articles show substantial durability and tend to retain the new deformation even under adverse conditions of weather and use.

It may thus be seen that there has been provided a novel and useful method and means for the production of decorative articles. By virtue of the method and means disclosed, relatively large production may take place with a low manpower requirement. This provides for a consequently reduced cost of production, and greater distribution, sale and use. The products manufactured in accordance with the process described are substantially uniform with respect to each other and full advantage is taken of the thermoplastic and/or thermosetting qualities of the material which is being worked.

I wish it to be understood that I do not desire to be limited to the exact details of construction shown and described, for obvious modifications will occur to a person skilled in the art.

I claim:

A device for producing embossed decorative articles by the use of burning gas and pressure comprising: a male die element having a plate-like body; a female die element having a plate-

like body, said female die element having a plurality of spaced receptacles; said male die element having a plurality of spaced male die members arranged so that all of said male die members are simultaneously receivable by said receptacles; first heating means secured to the body of the female die element, including a circularly arranged tube having a plurality of orifices disposed to direct gas emanating therefrom radially toward the point with respect to which the tube is concentric; second heating means secured to the body of the male die element, including a circularly arranged tube having a plurality of orifices disposed to direct gas emanating therefrom radially toward the point with respect to which the tube is concentric and means to reciprocate said die elements with respect to each other.

HENRY LISH.
